DEVICE FOR STRAIGHTENING BENT OR IRREGULAR AXLE HOUSINGS

Filed March 6, 1922

Patented July 24, 1923.

1,462,955

UNITED STATES PATENT OFFICE.

DAVID CAMP, OF CUMBERLAND COUNTY, NEW JERSEY.

DEVICE FOR STRAIGHTENING BENT OR IRREGULAR AXLE HOUSINGS.

Application filed March 6, 1922. Serial No. 541,294.

To all whom it may concern:

Be it known that I, DAVID CAMP, a citizen of the United States, residing in the county of Cumberland, post-office at Newfield, in the county of Gloucester, State of New Jersey, have invented a new and useful Device for Straightening Bent or Irregular Axle Housings, of which the following is a specification.

10 My invention relates to an improvement in a device for straightening an axle housing or the axle that has become irregular or distorted by bending or otherwise, the same embodying a beam that may be seated 15 on and attached to a straight or regular part of the housing, a member adapted to be coupled with the irregular portion of the housing, a fulcrum on said beam adapted to be seated adjustably on the housing adjacent to the bent or irregular portion thereof, and means for operating said member to exert a pull or draft on said irregular portion of the housing so as to restore the said portion to proper straightness.

20 The invention consists in rendering said fulcrum adjustable on said beam whereby the former may be set nearer to or further from the end of the irregular portion of 25 the housing according to the extent of said portion or its bent or distorted shape so as to effectively straighten the housing.

The invention is satisfactorily illustrated 35 in the accompanying drawing, but the important instrumentalities thereof may be varied, and so it is to be understood that the invention is not limited to the specific details shown and described, as long as they are within the spirit or scope of the claims.

40 Figure 1 represents a partial side elevation and a partial vertical section of a device for straightening axle housings embodying my invention.

Fig. 2 represents a top or plan view 45 thereof.

Fig. 3 represents a transverse vertical section on line 3—3 Fig. 1.

Fig. 4 represents a side elevation of a detached member.

50 Fig. 5 represents a bottom plan view of the member shown in Fig. 4.

Similar numerals of reference indicate corresponding parts in the figures.

Referring to the drawings.

1 designates a portion of an axle housing that has been bent or become irregular or otherwise distorted. 2 designates a horizontally extending beam having therethrough at one end the vertically extending opening 3, and in the other end on the upper side thereof the recesses 4. Depending from said beam adjacent to the opening 3 in the beam 2 is the fulcrum or strut 5 it being composed of a leg or prop having a T-head which is parallel with and bears flat against the underside of the beam 2 and has therein the bolts 7 which are on the exterior of said beam 2 and passed through said T-head and through the plate 8 which latter rests upon the upper side of the beam, the threaded ends of said bolts having thereon the nuts 9 for tightening said plate and head to the beam, and so retaining them and consequently the fulcrum tightly in position on the beam, it being evident that when said nuts are loosened the fulcrum is adapted to be moved to the right or left on the beam for purposes of adjustment, as will be hereinafter more fully referred to.

As stated the bolts 7 do not pass through the beam, but along the sides thereof, hence said beam is left solid, intact and strong, and as the bolts embrace the beam, the fulcrum 5 is held firmly on the beam and its head is prevented from being twisted off therefrom in lateral direction. As the main portion of the body of the beam is unpierced for the tightening bolts 7 said portion is not weakened so it is well enabled to endure the severe strain to which it is subjected in use without liability to fracture or break during the straightening operation.

10 designates an anchoring yoke which is adapted to straddle the straight or regular portion 11 of the housing and has the upper ends of its legs adapted to be connected freely by the cross bolt 10 with the clevis 12 whose crown 13 is adapted to be seated in either of the recesses 4 of the beam and thus sustaining the clevis on the beam and so suspending the yoke from the latter.

14 designates a bolt on the lower end of which is the eye or ring 15 which is adapted to be fitted over the irregular portion of the housing so as to take firm hold thereof,

the upper portion of said body passing freely through the eye 15 of the beam 2 and being threaded for engagement of the nut 16 which is adapted to ride on the 5 upper side of the beam 2 and when properly operated to draw up the bolt 14 and consequently the eye 15, as will be hereinafter again referred to.

The lower end of the fulcrum 5 is 10 caved as at 17 so as to be seated movably but steadily on the upper side of the irregular portion of the housing and prevented from slipping laterally therefrom.

The operation is as follows:—

15 The yoke is placed around the straight or regular portion 11 of the housing and connected with the beam by the clevis 12. The fulcrum 5 is seated on the housing adjacent to the irregular portion thereof, and 20 the eye 15 fitted over the end of the latter named portion, the beam being sustained by the fulcrum 5 on said portion 1 and steadied by the yoke and clevis and the eye and bolt on opposite ends thereof. The 25 nut 16 is now rotated whereby it raises the bolt 14 and with it the eye 15. The latter thus exerts an upper draft or pull on the bent portion of the housing while the fulcrum 5 preserves the position of the beam 30 and also allows the irregular portion of the housing to be turned up from the base of the fulcrum in a right line and so straightened to the required extent.

The nut 16 may now be loosened and the 35 bolt 10 withdrawn when the parts of the device may be dis-assembled and removed from the housing.

Attention is drawn to the fact that the fulcrum may be adjusted to the right and 40 left according to the length of the irregular portion of the housing and it is furthermore deflected from a right line so as to be reversed and adjustably seated on different places of said portion nearer to or further 45 from the end of the same according to the contours of the portion as the work of drawing up said portion may be successively performed and straightening the same progresses.

50 These adjustments of the fulcrum are readily performed owing to the movable connection of said fulcrum and the plate 8 with the beam by the bolts 7 and nuts 9, the latter, as evident, being tightened 55 when said adjustments are accomplished.

On the end of the portion 1 of the housing is the device 18 for examining the interior of the irregular portion of the housing to watch the work of straightening, the 60 same consisting of the tubular piece 19 which is adapted to enter said portion and have the human eye applied to the outer end of the bore of the piece, the effect of

which is evident. The piece is connected with the threaded collar 20 which may be 65 screwed to the end of the portion 1 of the housing and so removably retained thereon.

The T-head of the fulcrum provides a long surface for firmly connecting the fulcrum with the beam, and preventing the 70 fulcrum which is subjected to considerable lateral strain from being wrenched from the beam.

The plate 8 also forms enlarged bearings for the nuts 9 and assists in providing a 75 strong connection for the fulcrum member with the beam.

Having thus described my invention what I claim as new and desire to secure by Letters Patent, is:—

1. In a straightening device of the character stated, a beam having on opposite end portions respectively an anchor and a straightening member, and an intermediate strut, one end of the latter being adapted to be seated on the article to be straightened, and the other end thereof being provided with a T-head adapted to be seated on said beam, said head having lateral extensions projected beyond the opposite sides of said beam, a plate adapted to be placed on said beam opposite to said head, said plate having lateral extensions projected beyond the opposite sides of said beam, and tightening bolts adapted to be passed through the extensions of said plate and head exterior of said beam.

2. In a device for straightening a bent or irregular portion of an axle housing, a beam having thereon means for connecting it with the housing, a depending fulcrum member which is mounted movably on said beam and adjustable thereon in the longitudinal direction and provided with a T-head which is adapted to rest on said beam, a plate on the beam opposite to said T-head, and bolts in said head and plate passing therefrom on the exterior of said beam.

3. In a device for straightening a bent or irregular portion of an axle housing, a beam, means on the latter for connecting it with the housing, a fulcrum member adjustably depending from said beam and having a T-head which is movable on said beam in the longitudinal direction thereof, and nutted bolts connected with said head and engaging said beam for securing said fulcrum member in the position to which it is adjusted, said beam having thereon a plate through which said bolts are adapted to pass and which form bearings for the nuts of said bolts.

DAVID CAMP.
